TRUCK

Herbert Smith, 62 Whitman Drive, Brooklyn, N.Y.

Filed Dec. 23, 1959, Ser. No. 58,788

Term of patent 14 years

(Cl. D14—3)

Fig. 2.

Fig. 1 is a front perspective view of a truck embodying my new design; and

Fig. 2 is a rear perspective view of same.

The dominant features of my design reside in the portion shown in full lines.

I claim:

The ornamental design for a truck, as shown and described.
